MACHINE FOR GRINDING LAMINATED ARTICLES

Edgar D. Vancil, Cincinnati, Ohio, assignor to Cincinnati Grinders Incorporated, Cincinnati, Ohio, a corporation of Ohio

Application March 26, 1936, Serial No. 70,982

12 Claims. (Cl. 51—92)

This invention relates to grinding machines, and more particularly to a special automatic machine for grinding rectilinear grooves.

One of the objects of this invention is to provide a machine for performing a grooving operation which cannot be readily accomplished on conventional machines without a multiplicity of adjustments.

A further object of this invention is to provide an improved simplified mechanism for deflecting and holding a vehicular spring as under load conditions, and forming a configuration therein which could not be formed otherwise except by a multiplicity of operations.

15 An additional object of this invention is to provide a special automatic machine for grinding grooves in automobile springs for the attachment of side-sway eliminators.

Other objects and advantages of the present invention should be readily apparent by reference 20 to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

30 Figure 1 is an elevation of a machine tool embodying the principles of this invention.

Figure 2 is a plan view of the machine shown in Figure 1.

35 Figure 3 is a vertical section on the line 3—3 of Figure 2.

Figure 4 is a cross section on the line 4—4 of Figure 3.

Figure 5 is a section taken on the line 5—5 of Figure 3.

40 Figure 6 is a section on the line 6—6 of Figure 5.

Figure 7 is a section on the line 7—7 of Figure 3.

45 Figure 8 is a section on the line 8—8 of Figure 7.

Figure 9 is a section on the line 9—9 of Figure 7.

50 Figure 10 is a section on the line 10—10 of Figure 1.

Figure 11 is a section on the line 11—11 of Figure 6.

55 Figure 12 is a section on the line 12—12 of Figure 5.

Figure 13 is an elevational view of the work holding carriage.

Figure 14 is a diagram of the electrical control circuit.

Figure 15 is a diagram of the fluid pressure control circuit.

Figure 16 is an expanded view of the one revolution cam track.

The machine comprises, in general, a large table, part of which is fixed, and whereupon a 10 laminated article may be assembled and manipulated, and the other part of which is movable whereby relative adjustment between the article and a tooling element, such as a grinding mechanism, may be effected.

15 Referring to Figures 1, 2, and 4, the reference numeral 10 indicates the bed of the machine and upon this is supported a movable table portion 11 and a fixed table portion 12, these portions lying in the same plane.

A work supporting carriage 13, such as shown 20 in Figure 13, is provided for manual movement from a work loading position, indicated generally by the reference numeral 14, in Figure 2, to a tooling position, indicated generally by the ref- 25

erence numeral 15 in the same figure. When the carriage is in the work loading position, a work piece 16, which may be a laminated vehicu- 30

lar spring, such as used on automobiles and the like, may be placed in the fixture and located by a pin 16' passed through the eye in the end of the spring and resting in a semi-circular notch formed in the end of the work holder. A second pin 16'' may be passed through the eye in the other end of the spring and slidably rested on 35

the upper edge of the sides of the work holder. A power operated ram, such as 17, is moved down- 40

ward to flatten out the laminated article into the form in which it is shown in Figure 4. This ram is attached to a piston, not shown, which is 45 movable in a cylinder 18 which is supported in overhanging relation with respect to the fixed table portion 12 and the work carriage is man- ually movable to a position under the ram where- by upon movement of a control valve 19, the ram may be power moved downward a suitable amount to flatten out the article.

By reference to Figures 1 and 13, it will be seen that the work carrier has two pairs of upstanding side supports 20 and 21 and holes 50 22 and 23 are drilled through each pair. When the article has been sufficiently flattened, bolts, such as 24 shown in Figures 1 and 4, may be passed through these holes to hold the work in position. The ram 17 may now be elevated and 55

the carrier moved as on the supporting rollers 25 from the work loading position to the tooling position shown in Figure 2.

The work carrier has a pair of countersunk holes 26 formed in the uprights and the carrier is positioned so that these countersunk holes are in line with dowel pins 27 having cone-shaped heads 28. The dowel pins are carried in one jaw 29 of a vise, the other jaw 30 being power operable to move the carrier against the jaw 29 and in so doing cause the cone-shaped heads 28 to enter the countersunk holes 26, and at the same time slightly raise the carrier from the table so that it will clear the same.

15 The jaws 30 are pivotally connected to the lower end of bell cranks 31 and 32 which are, in turn, connected to an equalizer cross bar 33 pivotally connected at 34 to the end of piston rod 35. This piston rod carries a piston 36 which is movable in a cylinder 37. This cylinder is connected as shown in Figure 15 by a channel 38 to port 39 of a control valve 40 having an intake pressure port 41. The valve plunger 42, which may be manually rotated by a handle 43, shown in Figure 1 of the drawings, serves to connect the pressure port 41 to the port 39 whereby the work carrier may be clamped to a vertically movable slide 44 which is, in turn, carried by a cross slide 45. It will, of course, be evident that since the piston and cylinder above mentioned must be carried by the vertical slide 44 that suitable flexible connections must be made between the cylinder and the control valve 40 which is located in the bed of the machine with 35 its operating handle in a convenient place for access by the operator.

Attention is invited to the fact that the dowel pins 26 also serve to properly locate the work with respect to a pair of grinding wheels 46 and 47 which are located opposite the slide 44 and are suitably spaced on a spindle 48 to grind grooves in the work in the desired spaced relation. Each wheel is also of a width corresponding to the width of groove desired in the work. 45 These grinding wheels may be rotated by suitable power means, not shown, and may also be provided with a suitable truing mechanism such as that indicated generally by the reference numeral 49 in Figure 1. Since such truing mechanisms are well known in the art, further description thereof is not believed to be necessary.

Power operable mechanism has been provided for reciprocating the slide 44 vertically to traverse the work tangentially relative to the faces 55 of the grinding wheels and for automatically infeeding the work toward the face of the grinding wheels to determine the depth of the groove. This mechanism is driven by a prime mover 50. This motor is started by the automatic closing of 60 switch 51 which is controlled by the electrical circuit shown in Figure 14. This circuit has a pair of switches 52 and 53, the former of which is held open by a cam 54 attached to the rear of a sub-support 55 when the same is in a retracted position, and the latter switch is held closed by a similar cam means attached to the rear of slide 55.

Since the switch 53 was closed by the previous return of slide 55, it completed a circuit from the 70 main power source 56 through line 57, switch 53, line 58, coil 59 and line 60 to the other line 61 of the power source. Energization of the coil 59 closed switch 62 and this automatically locked the switch, because even although switch 53 will 75 be opened when the slide 55 starts forward, a

second switch 63, being closed, will short circuit switch 53 and maintain the coil 59 energized. By the switch 52 being closed, it is now possible when the slide 55 moves forward and automatically opens switch 53 and closes switch 52, to energize the starting coil 64, one end of which is connected by line 65 to the power line 61 and the other end connected through the line 66, closed switch 52, line 67, closed switch 62 and line 68 to the other power line 56.

When the valve 42, Figure 15, is moved to its starting position, shown in this figure, the pressure admitted to line 38 also passes through line 69 to the lower end of cylinder 70. This causes upward movement of the container piston 71 and piston rod 72 which, as shown in Figure 3, has rack teeth 73 formed thereon in mesh with gear 74. The gear 74 is keyed to the end of shaft 75, as shown in Figure 5, which has an eccentric arm 76, Figure 11, attached to the end thereof and interengaging a link 77, as more particularly shown in Figure 6. This link is connected by a pin 78 to the rear end of slide 55.

Referring now to Figure 3, it will be evident that upon admission of fluid to the lower end of cylinder 70 the piston 71 will move upward and thereby through the rack and pinion connection rotate the eccentric 76 in a counterclockwise direction and thereby move the sub-support 55 and the work carried thereby into grinding relation with the grinding wheels. Simultaneously, this movement will effect the opening of switch 53 and the closing of switch 52 to start actuation of the prime mover 50.

The prime mover is connected through the following mechanism to slide 29 to effect reciprocation thereof. As shown in Figure 7, the armature shaft of the prime mover has a sprocket wheel 79 which is connected by a chain 80 to a sprocket wheel 81 secured to the end of shaft 82. 40 This shaft, as shown in Figure 3, has a pinion gear 83 keyed to the end thereof in mesh with gear 84 keyed to the end of shaft 85. This shaft is anti-frictionally supported in the housing of slide 45, and on the forward end is provided with a crank arm 86 which is connected by link 87 to a pin 88 projecting from the rear of slide 29. It will be apparent that as the shaft 85 is continuously rotated, the slide 29 will be vertically reciprocated, thereby moving the work tangentially relative to the face of the grinding wheels.

It is also necessary, in addition to reciprocating the work, to gradually feed the work into the grinding wheels in order to effect the desired depth of groove. To this end, the shaft 85 has a spiral gear 89 secured thereto, as shown in Figure 3, which intermeshes with a spiral gear 90 keyed to shaft 91. Through this means, the shaft 91 is rotated at a very slow rate relative to shaft 85 and the latter serves to drive an infeeding mechanism. In furtherance of this end, the shaft 91 has attached thereto the member 92 in which is formed a cam groove 93 for receiving a roller 94 attached to the end of a crank arm 95. This crank arm, as more particularly shown in Figure 8, is secured to a shaft 96 which has splines 97 formed in one end thereof for rotating a gear sector 98. This gear sector, as shown in Figure 5, intermeshes with a pinion 97' keyed to shaft 98', which shaft, as shown in Figure 6, has a screw thread 99 cut on one portion thereof. This screw thread is rotated relative to a nut 100 which is held against rotation by a worm 101 intermeshing with gear teeth 102 cut on the periphery of the nut. A spring 103

may be interposed between a fixed portion of the nut and a movable portion 104 thereof for eliminating backlash.

Attention is invited to the fact that the gear 5 sector 98 is mounted in a housing 105 which is attached to the sub-support 55 and therefore it is necessary to provide the spline connection in order that the shaft 96 may move with the slide 45. The housing 105 also contains the gear 97 10 and a thrust bearing 106 which holds the shaft 98 against axial movement, whereby upon rotation of the screw 99 the nut 100, which is held against axial movement in the slide 45, will cause the slide to move relative to the sub-support 55.

15 Manually operable means have also been provided for effecting relative adjustment between the support 45 and the sub-support 55 for set-up purposes and the like, and this means, which is more particularly shown in Figure 10, comprises 20 a hand wheel 107 operatively connected to a shaft 108, the latter being anti-frictionally journaled in the slide 45. A pinion 109 secured to the end of this shaft intermeshes with a gear 110 fixed with shaft 111 to which is secured a worm 101 25 meshing with a worm 102. The worm and worm gear are those previously mentioned, which normally hold the nut 100 against rotation, but upon rotation of the hand wheel 107, when the screw 99 is stationary, it will be apparent that relative 30 rotation between the screw and nut can still be effected and the slide 45 adjusted relative to the sub-support 55.

Referring now to Figure 3, the shaft 85 serves as a common actuator for a first branch transmission which reciprocates the vertical slide 29 35 and for a second branch transmission, which continuously effects infeeding of the work during reciprocation. Due to the reduction in rate effected by the spiral gears 89 and 90, the shaft 91 40 is rotated at a very slow speed, whereby the slide 29 may make a large number of reciprocations for one revolution of the shaft 91. Means are provided whereby the shaft 91 is, in effect, a one revolution shaft, whereby, after the shaft 45 has made one revolution, certain controls will be operated to stop the grinding operation.

In view of this, the cam groove 93 in the member 92 has been so formed that during one revolution thereof it will effect the necessary infeeding, followed by a subsequent dwell for cleanup purposes, and then a rapid retraction of the parts. The shape of this cam groove is shown in expanded view in Figure 16 in which the ordinate 112 indicates the starting point, and from this point through an angle of substantially 252 degrees to the ordinate 113 a continuous infeed is effected, and during the next 36 degrees the cam path is straight so as to provide a dwell for cleaning up purposes.

60 During the next 72 degrees the cam path is so formed as to effect a rapid retraction of the work slide relative to the grinding wheel.

The shaft 91 has a dog carrier 114 to which is attached a dog 115. A pair of radially arranged 65 plungers 116 and 117 are provided for actuation by the dog and these plungers operate switches 63 and 118 respectively. As viewed in Figure 9, the dog wheel 114 rotates clockwise whereby the switch 63 is operated first and, as seen in Figure 70 14, when this switch is open, it de-energizes the coil 59 because the switch 53 is also open at this time and this causes automatic opening of switch 62. The current flowing through the coil 64 which holds switch 61 closed now travels through line 66, closed switch 62 and closed switch 61 to

line 68. Therefore, upon continued movement of the dog 115 and opening of switch 118, the coil 64 will be de-energized and the switch 51 will be automatically opened to stop the motor 50. At the same time, a brake 119, which is held open by the solenoid 120 coupled across the motor lines by branches 121 and 122, will become de-energized and a spring 123 will apply the brake to prevent overrun of the motor.

The machine is now automatically stopped and 10 the operator may throw the valve 42, shown in Figure 15, clockwise to connect the pressure port 41 to the line 124, which will cause downward movement of the piston 71 and thereby retraction of the sub-support 55 and parts carried 15 thereby to move the work away from the grinding wheels. This pressure also flows to the upper end of cylinder 37, causing downward movement of the piston rod 35 and release of the clamp jaws 30. It will be noted that the return from 20 this cylinder must pass through a throttle valve 125 because the check valve 126 will be automatically closed at this time, thereby delaying the release of the work until the sub-support 55 has been fully retracted.

When the sub-support has reached its retracted position it will open switch 52, Figure 14, and close switch 53, thereby energizing coil 59 and closing the switch 62, which thus conditions the circuit so that upon the next forward movement of the slide 55 the closing of switch 52 will energize coil 64 and close the motor starting switch 51.

The work carrier 13 may now be rolled out onto the table 12 and turned around on the table and 35 reinserted in the carrier clamping jaws for grinding grooves in the other side of the work.

There has thus been provided a simple mechanism whereby a vehicular spring may be power deflected and held as under actual conditions of 40 use, and a configuration machined therein by a simple operation, while so held, and which could not be formed otherwise except by a multiplicity of operations.

I claim:

1. A grinding machine having rotatable grinding means, means for supporting and moving work in operative relation to the grinding means including a sub-support, a work support mounted thereon for relative movement along paths angularly related to one another, power operable means for reciprocating the work support along one path of its movement and uni-directionally along its second path of movement, power operable means for moving the sub-support to position the work support in a tangential plane relative to the grinding means, and means responsive to said positioning movement of the sub-support to initiate actuation of both of said power operable means.

2. In a machine tool having a slide power movable relative to a tooling element to effect a machining operation, the combination with the slide of a removable work holder, cooperating means on the slide and work holder for locating one 65 with respect to the other and thereby positioning the work in desired relation to the tooling element, and anti-frictional supporting rollers carried by the work holder whereby the same may be readily moved from the slide to a work loading 70 position.

3. A grinding machine having a grinding wheel, a first slide movable in one plane, a work slide carried thereby and movable in a second plane, means carried by one of said slides for 75

reciprocating the other relative thereto, means for feeding the first slide, a prime mover for driving both of said means, a separate power operable device for moving the slides into grinding position, and means automatically operable upon said last-named movement for starting the said prime mover.

4. A grinding machine having a grinding wheel, a first slide movable in one plane, a work slide carried thereby and movable in a second plane, means carried by one of said slides for reciprocating the other relative thereto, means for feeding the first slide, a prime mover for driving both of said means, a separate power operable device for moving the slides into grinding position, and means automatically operable upon said last-named movement for starting the said prime mover, said automatically operable means including a power operable switch, and a pilot electrical control circuit including a switch adapted to be closed by the movement of said slide to a grinding position.

5. In a grinding machine, the combination of a grinding wheel, of means for operatively associating a work piece therewith for grinding thereby, including a first slide having a power operable clamp mounted thereon, a removable work holder adapted to be inserted in said clamp, and thereby secured to the slide, a supporting slide for the first slide, a sub-support for moving all of said parts into a grinding position with respect to the grinding wheel, and fluid operable means for actuating said clamping means and said sub-support.

35. 6. In a grinding machine, the combination of a grinding wheel, a slide reciprocable relative to the grinding wheel and having a clamping jaw, a removable work holder adapted to be inserted in said jaw, fluid operable means for holding the work carrier in said jaw, a sub-support for said slide, fluid operable means for moving the sub-support and thereby the slide into grinding position with respect to the grinding wheel and retracting the same, a common control valve for each of said fluid operable means and movable 45 to a position to effect simultaneously unclamping of said jaws and retraction of the sub-support, and means to delay operation of said unclamping means until the sub-support has been retracted.

7. In a grinding machine, the combination 50 with a grinding wheel, of a slide movable toward and from the grinding wheel, a work table and a prime mover carried by the slide, means operatively connecting the work table to the prime mover for reciprocation thereby and for infeeding the same relative to the slide, an electrical control circuit including a power operable switch for the prime mover, a pilot control circuit for said switch including a first pair of pilot switches operable by the slide for closing said power operable switch, and a second pair of pilot switches successively operable by the prime mover for opening said power operable switch.

8. In a grinding machine having a grinding wheel, and a work supporting slide movable in one direction to reciprocate the work in operative engagement with the grinding wheel, and in a second direction to infeed the work relative to the grinding wheel; of a prime mover, means coupling the prime mover for reciprocation of the slide, a one revolution cam coupled to the prime mover for infeeding the slide, said cam having a first cam portion for continuously infeeding the slide, a second portion for causing a dwell in the slide and a third portion for rapidly retracting the slide, and means simultaneously operable at the end of one revolution of the cam to stop the prime mover.

9. In a grinding machine, the combination of a grinding wheel, of means for operatively associating a work piece therewith for grinding thereby, including a slide, a fluid operable piston carried thereby for clamping work therein, a sub-support for the slide including a fluid operable piston for causing positioning of the first slide in a grinding plane with respect to the grinding wheel, and a single control valve for controlling actuation of each of said pistons.

10. A grinding machine having a grinding wheel, a work support, power operable means for effecting multiple reciprocations of the work support relative to the grinding wheel, a rotatable mechanism coupled for actuation by said power operable means at a slow rate as respects the period of reciprocations of the work support, means coupling said mechanism for feeding the slide toward the grinding wheel, and means responsive to one revolution of said mechanism for stopping said power operable means.

11. In a grinding machine for grooving a laminated body or the like, the combination with a grinding wheel support, of a mechanism opposing the wheel for determining presentation of work in operative relation thereto, including a support for introduction of a work piece, a work carrying slide adjacent the support and reciprocable in a direction tangentially of the grinding wheel face, a first power operable means for raising the work from the support and securing same on the reciprocable slide, additional power means for effecting multiple reciprocations of the slide and attached work tangentially as respects the grinding wheel face, means operable in timed relation with the reciprocations of the slide for effecting a gradual movement of the slide and work in a radial direction as respects the operative face of the grinding wheel, and means for discontinuing both the feeding and reciprocating movements.

12. A machine as specified in claim 11 in which the discontinuing means comprises a single revolution control device operable by and in timed relation with the power driven feed mechanism.

EDGAR D. VANCIL.
